UNITED STATES PATENT OFFICE.

PAUL L. CLARK, OF BROOKLYN, NEW YORK.

PHOTO-ELECTRICAL TRANSMISSION APPARATUS.

Application filed December 22, 1925. Serial No. 77,020.

My invention relates to improvements in apparatus for the transmission and receiving of electrical or electro-magnetic impulses either by wire or radio of point by point, line by line, scenes at one location so that an image of the said scenes may be produced simultaneously and registering accurately with the point by point light values of the original scene, as understood in the art; and the object of the present invention is to provide a simple and efficient optical, electrical and mechanical arrangement applicable to both the receiver and transmitter. Additional objects are pointed out in the following specification and claims, and shown in the drawings.

I attain these several objects by the mechanism illustrated in the accompanying drawings, in which—

20 Figure 1 is a plan view of part of the mechanism used for both or either the receiver or transmitter; Fig. 2 is a front elevation of Fig. 1, with parts broken away for clearness; Fig. 3 is a section of Fig. 2 on 25 3—3; Fig. 4 shows a part of a typical filament of a light source used in Fig. 8; Fig. 5 shows a speed varying or position changing element; Fig. 6 shows a typical light source; Fig. 7 shows a grid such as used conjunctively in Fig. 8; Fig. 8 is a plan view of part 30 of an optical system for the receiver, or with slight modifications for the transmitter; Fig. 9 is a section of Fig. 8 on 9—9; Figs. 10 and 11 are enlarged views of details of 35 the optical system; Fig. 12 is a plan and Fig. 13 is an elevation of a speed changer or regulator; Fig. 14 is a diagram of connections for regulating the speed of the driving motor for the apparatus shown in Figs. 1, 40 2, 3; and Fig. 15 is a series of diagrams which show the individual effect on the optical system caused by the rotation or oscillation of the several cooperating or correlated elements of the apparatus. Fig. 16 is 45 a detail of a modified receiver optical system; Fig. 17 is a detail of beam and lens intersection.

Similar numerals refer to similar parts in the several views, unless otherwise noted.

50 In Figs. 1, 2 and 3, a motor 1 drives a shaft 2 connected to a speed regulator 4 (see Figs. 5, 12 and 13) connected to the long coaxial shaft 5 turning in bearings 11 and driving the gear 7, worm 12 and lens carrying wheel 25. Gear 7 meshes with gear 8 connected to shaft 10 in bearings 16 and

drives the polygonal mirror group 27 which revolves in a horizontal plane substantially bisected by the axis of the upper lens 26 in the wheel 25. Meshing with the worm 12 is a gear 13 on a shaft 14 which runs in bearing 16 and ends in the speed regulator 4 which is attached to coaxial shaft 15 passing through bearing 17 and driving a uniform motion cam 18 attached to a quadrant shutter 19 and reciprocating a roller 20 attached to rocker arm 21 fastened to spindle 22 in bearings 23 and to an oblique plane 70 mirror (this mirror may be concave or convex if desired, to vary the characteristics of the optical train) symmetrically disposed in front of the upper lens 26 in its central position. The function of this mechanism is to 75 secure a relative location, rotation and oscillation of the several cooperating optical and mechanical elements to the end that a pencil of rays of controlled intensity passing through the lens 30 be intercepted by the 80 shutter 19, focused substantially upon the periphery of the mirror disk 27, reflected therefrom to register substantially upon and follow the approximate path of travel of the upper lens 26 during its transit across a 85 given arc (approximately equal to chord e , Fig. 8), said lens being of such focal length as to converge the rays to a focus at a given distance therefrom (which, in Fig. 2 is, after reflection by the mirror 24, at approximately the focal plane 40). The ratios and angular 90 position of the gears, cam and other factors is such that the opaque portion of the shutter 19 cuts off the light beam 36^a during the return motion of the cam 18; the angular velocity of the disk 25 and the arc 95 traversed by each lens 26 is such as to cause each of said lenses when passing the field in front of the mirror 24 to successively intercept the unidirectional intermittently reflected beam 36^b from each of the mirrors 28 100 of the group 27 during the rotation of said group and the simultaneous rotation of said disk 25, the planes of rotation of said disk and said group being preferably at right angles, and the arc (f, Fig. 8) subtended 105 and traversed by each mirror in a given interval being proportional to that subtended by each lens 26 in the same interval the duration of which is the time required to register all component light point values 110 comprising one transverse line or arc of the transmitted picture. The gear ratios and the angular velocity and position of the cam

55

18 and shutter 19 are such that the mirror 24 is oscillated about fifteen times per second for moving picture transmission, and less for still pictures, and the light beams 37, 38, 5 39 reflected by it to focus upon the surface 40 traverse such a distance across the field of view at 40 as to secure the proper periods of time and spacing between the delineation of successive transverse lines of the transmitted picture, it being understood that the successive lines (as produced by each of the successive mirrors 28 of the group 27, which cooperate, follow and register each successively with one of the lenses 26 during its 10 passage across an arcuate area upon which are substantially superimposed in rapid succession beams of variable intensity proportional to the true light values of each picture point or area for projection to its corresponding registering position on the focal surface 40) are spaced or their edges juxtaposed or slightly overlapped by the tipping of the mirror 24 to cause the beam of light reflected by it to focus upon and entirely embrace, 15 in its arc of reciprocation, the height of the desired view upon the surface 40, the arc of oscillation of the mirror 24 during the interval required for the passage of a single lens 26 across the field of view, being very small 20 as compared to the arc traversed by said lens; so that as many lenses pass the field of view during the registering of one complete image as there are transverse lines comprising the whole picture; and the cam 18 makes 25 only three-fourths (provided a three-to-one ratio cam is used) revolution during which the mirror 24 is optically operative in conjunction with the shutter 19, the remaining one-fourth revolution of the cam being required to return the mirror to its starting 30 position for the beginning of another cycle. The lens carrier wheel 25 continues to revolve at uniform speed, but no light passes to the lenses, as the shutter is so geared and timed as to intercept the light rays during 35 the return stroke of the mirror to its starting position. Transverse deflection, positioning and timing of the picture points is accomplished by the uniformly spaced, identically mounted, accurately matched lenses moving at uniform velocity and supported by the disk 25 equally distant from its center of rotation, so that each lens functions successively in identical manner, in cooperation 40 with the mirrors comprising group 27, each of which traverses a line or arc; and vertical deflection, positioning and timing of these lines is secured by the mirror 24 which moves at, preferably a uniform rate of speed 45 and the amplitude of which is controlled by the design of the cam 18 and connecting arm 21. The above-described optical and mechanical system applies particularly to the device when used as a receiver; but by 50 considering the direction of the light rays 55 reversed (to that shown by the arrowed lines on the light beams) the apparatus becomes a transmitting instrument if a photo-electric cell be placed at the focus of or in the path of the rays passing in reverse direction 60 to or through the lens 30, Figs. 1 and 8, provided said cell be connected through a suitable circuit, as understood in the art. The mirror group may be made of reflecting metal, each mirror being identical, all mirrors contacting on their edges, and each subtending an equal angle with respect to the axis of rotation of the group. The devices 65 4 (see Figs. 5 and 12) are used for independently bringing into synchronism and step the mechanism either as a whole or each element separately, devices for the same purpose having been shown in British Patent 218,766. All spindles should be provided with collars (not shown) to prevent end play, and set screws to secure the several parts in proper alinement, and the optical parts enclosed in a light-tight housing, as is customary. The transmitter need not necessarily be of the same type as the receiver, provided the correct picture proportions are maintained. Means for deflecting the light beam to approximately 70 traverse and follow lenses or apertures in a rotatable disk are described in my copending application Ser. No. 655,027, which also shows several types of lens mountings applicable to the lens wheel 25.

In Fig. 4 the diameter c of the filament 35 should be preferably less than one-half 75 of the spacing h and width d of the grids as shown in Figs. 7 and 8. The length of the filament may be as desired; but ordinarily should be about twice its diameter.

In Fig. 5, the driving shaft 2 and driven shaft 5 are attached to gears 48, 47, and turn 80 in bearings in the frame 51. Gears 49, 50, turn on shafts integral with the frame 51. By turning the handle 52 about the axis of the shafts 2, 5, angular displacement between the shafts 5 and 2 is attained.

In Fig. 6, the incandescent lamp filament 35 is of small diameter, and when this source is used in connection with the optical system of Figs. 8, 9, 10 and 11, the mirrors 32, Fig. 8; 32^a, Fig. 11, may be of any desired length to embrace the light rays from the required length of filament; although in Figs. 8 and 9 the width of the beam at its plane of interception by the mirror 32 should be very small, this restriction does not apply to the system shown in Fig. 11.

In Fig. 7, the grid 31 of opaque material has apertures 54 and opaque strips 55 preferably uniformly spaced and all of identical width and parallel, so that the widths d and h are ordinarily equal. When used as coacting grids, as in Fig. 8, the number of bars may be equal or different, as desired, and the dimensions and spacing varied to 120

meet optical requirements, depending upon the spacing, characteristics, focal lengths and design of the several lenses, mirrors and grids distributed for most useful and efficient service on the optical axis. Similar grids are shown in my copending application, Ser. No. 715,350.

In Figs. 8 and 9, rays 36 from the source 35 are received upon and refracted by the accurately ground lens 34. Some of the rays are intercepted by the grid 31^a and some rays pass through to focus upon or near the mirror 32 which is an oscillograph mirror or other light deflecting device responsive to photo-electric signals emanating from a sending station, as described in my copending applications Ser. Nos. 715,350 and 13,306, the deflection of this mirror for maximum signal strength being sufficient to cause the light and dark strips comprising the image of grid 31^a to fall upon, register with, and to be superimposed over respectively the apertures and bars of grid 31; and for zero deflection to cause the light transmitting areas of the image of grid 31^a to register upon and be intercepted by the opaque parts of the grid 31, so that practically no light from the source 35 reaches the lens 30. In case inverse values of picture point light values is transmitted by the sending station, the relative action of the grids images should be reversed from that stated above, so that a maximum received impulse would cause a superimposition of the dark image of grid 31^a to be superimposed over the grid 31. The grids are preferably disposed adjacent the lenses as shown, and between the mirror 32 and the lenses, although they may be for equally good results placed either side of the lenses. For best results the lenses and all parts of the mechanism should be made with extreme accuracy and precision. The optical system, as thus far described, comprises a light valve controlling the strength, proportional to photo-electric impulses, of the pencil of rays received upon the mirror 28 of the group 27. The relation between the distance *g* (between the central plane of the lens wheel 25 and the point of reflection of the rays from the mirror 28), the chord *e* (across the arc of travel of the optical axis of the lens during its functioning period), and the angle *f* (subtended by each mirror 28), should be approximately such that

$$f = \tan^{-1} \frac{e}{2g}$$

The mirror group 27 should ordinarily comprise thirty or more mirrors, and the disk 25 should have eight or more lenses of identical characteristics and satisfying the optical conditions shown in the drawings. When used as a transmitter, the grids and mirror 32 should be omitted and a photo-electric cell substituted for the mirror. In Fig. 9,

are shown three positions of the pencils 37, 38, 39, focused upon the surface 40, which ordinarily is not a true plane, as pointed out in the description of Fig. 15, and if a screen be placed here the image may be viewed directly; if, however, it is desired to project the aerial image formed at 40 to a larger screen, an objective lens 46 should be used disposed on the optical axis and focused upon the surface 40 and the said screen (not shown).

In Fig. 10, the incident pencil of rays is focused upon a circle 44 circumscribed around the polygon formed by the contacting mirrors 28, as shown by the arrowed lines.

In Fig. 11, an oscillograph mirror 32^a is shown completely embraced in three typical pencils of rays 56, 57, 58, from a source of greater diameter than shown in Fig. 8. Since it is practically impossible to secure a point source of light of sufficient intensity for practical projection, it is essential that either the source or the mirror be of dimensions determined by the size of the points of light at their intersection with the screen or the focal plane 40, Fig. 9; since if the point of light [which is in reality (for best results) an image either of the light source or of a cross-section of the beam adjacent or at the oscillograph mirror] be too large, it is evident that the adjacent picture points on the plane 40 will be blurred due to overlapping, resulting in a loss of clearness; and if the points are too small, it is seen that a picture of less than maximum brilliancy is secured. Consequently, the size or luminous area of the source is of utmost importance; since it—together with other optical factors—determines the practicability of the apparatus. In other words, there must be somewhere in the optical train a means for limiting the picture point size, and this is accomplished by applicant either by the use of a small light source, as in Fig. 8, or by a small diameter oscillograph mirror, as in Fig. 11; or both. It is evident that the lenses, light source, grids, shutters, oscillograph mirror, mirror wheel and oscillating mirror are to be suitably alined on a given optical axis, or on a plurality of intersecting optical axes, as understood in the art, and that the light beam should be approximately symmetrical with respect to said axis, or the plane of said axis.

In Figs. 12 and 13, gears 67 and 69 are free to turn on the coaxial shafts 72, 72, held by the frame 73. Gears 66, 68 are attached to coaxial shafts 2, 5, which turn in the frame 73 and are at right angles to shafts 72, and are the driving and driven shafts, as shown in Figs. 1 and 2. Lugs 71 are attached to shafts 72, and to these lugs is rigidly attached the arms 112 of the metal member 75 having a hub 76, so that the entire mechanism is free to revolve on shafts 2 and

5 as an axis. The handle 85 has a bearing 88 on shaft 2, which bearing extends upwardly to form a sleeve 87 on which is secured a flanged insulator 89 which securely holds a 5 contacting arm 90 bearing on a coiled resistance wire 92 grounded to the member 75 by a screw 95; so that if the handle 85 be turned about shaft 2, the contact travels over different turns of the coil 92 and thereby varies 10 the length of resistance wire between the point of contact and the ground connection. Lugs 86 on the handle 85 bear against flexible springs 79 rigidly held in the members 81, 81 pivoted on studs 82 attached to the member 75 and adjustable by means of screws 15 84 in lugs 83, and screws 78 in lugs 77 integral with the member 75. The adjustment of screws 78 should be such as to aline the springs for zero pressure against and in 20 contact with the lugs 86 when the handle 85 is in approximately central position, as shown. The adjustment of screws 84 should be such as to produce a force in the springs 79, 79 at their points of contact with lugs 25 86, equal to the counter force required at the said points of contact to overcome the friction produced by changing the angular position of the parts rotatable about the shafts 2, 5, including sliding friction of the contact arm over the resistance 92, when the 30 apparatus is running at normal synchronous speed. The relation between the strength and elasticity of the springs 79, in comparison to the resistance of the coil cut out of, or 35 added to the circuit, should be such that any change in the angular velocity or speed of (i. e., overcoming inertia or adding or reducing momentum) rotating or oscillating masses produced by the turning of the member 75 and its correlated parts through any 40 given angle will add to or subtract from the normal driving power of the prime mover at synchronous speed, in such manner as to automatically provide an instantaneous 45 variable power increment to the motor independent of the normal synchronous speed power requirements, the amount of added or decreased power being substantially proportional to the deflection produced in either 50 one of the springs 79, 79, by turning the handle 85. If the motor is assisted by turning the handle 85, less power will be required; if the motor is retarded, more power will be required to supply the force 55 equal to and counter to the retarding force, in order to maintain synchronous speed under constant load. The control of power to the motor may be accomplished in any well known manner, and I have here shown the 60 regulation as being made by the introduction of the variable resistance 92 in series with the field circuit 90, 96, 97, 98, 99, 102, 101, metal member 75, 95, of a constant speed shunt wound motor 100 (corresponding to 65 the motor 1, Fig. 1), supplied from a suitable

source 102. When more than one regulating or compensating device is used, as is necessary in Fig. 1, the regulating circuits on all the regulators may be connected in series or multiple, in order to deliver at the normally excited motor field a net current change equal to the algebraic sum of the several instantaneous current changes (whether positive or negative, depending upon whether the motor is retarded or accelerated by the 70 manual turning of the handle 85) when one or more of said regulating devices be adjusted separately or simultaneously. These changes in motive power should ordinarily be proportional to and simultaneous with the deflection produced in one or more of the tension springs 79, 79, by applying the necessary torque either manually or otherwise to rotate the handle 85, so as to overcome the friction of the system to be rotated or moved, the power to overcome inertia being supplied by the motor whose field is weakened or strengthened proportionally to the deflection produced in the springs 79, 79 75 when the position of the gears and parts connected to them is rotated by turning the said handle, which turning is for the purpose of phasing either the picture line or point positions on the screen to register with the picture sent or broadcasted by the transmitting station apparatus. This device is applicable to any type of mechanism requiring delicate speed adjustments, or changes in phasing, speed or position of any moving parts with relation to the position or speed of any type of driving mechanism connected to drive said moving parts. It is known that varying the field strength of a shunt wound motor varies its speed; or, considering the speed as constant, varying the field 80 will automatically produce an inverse variation in armature current to provide changes in power as required. 85

In Fig. 14, a battery 103 is connected across the terminals of an adjustable resistance 104 having a slider 105 making contact therewith; the combination of this resistance and slider being analogous to that of coil 92 and slider 90, Fig. 12. The slider is connected to the grid of an audion the plate of which is connected to a solenoid 108, so that as the grid current varies, the plate current is amplified to move an arm 109 attached to the solenoid plunger and vary the characteristics of a field rheostat or other regulating means 110 suitably cooperating with a driving device (not shown). 90

In Fig. 15, E is the position of the plane of deflection of rays from the edge, and M the plane of deflection from the middle of one of the mirrors on the disk 27, the action of this disk in revolving being to produce an out-of-focus effect on a plane surface, so that the optical plane for the rays from the edges of the mirror is beyond the optical 100

plane for the rays from its middle or intermediate points; so that since this disk 27 revolves in a horizontal plane, the distortion is apparently such that, for best utilization 5 of the rays by the lenses in the wheel 25, the surface traversed by the lenses in the wheel should be (as viewed in a horizontal plane) convex, as shown at H. However, a compensating effect is secured, since the distortion 10 which would be produced by the lenses 26 if the rays were directed to fall upon them in a true plane is neutralized by the rays actually striking them in beams of a length which is greater for the said lenses 15 in their outside than in their intermediate positions, so that the resultant of the two curved focal surfaces H and H¹ is to produce a substantially true and uniform focal distance for the rays which pass through the 20 lenses 26. E¹ is the position of the plane of refraction of the lenses 26 at the side or edge of their operative arc of travel, and M¹ is their position at the middle of said arc, P¹ and Q¹ being their respective foci. The 25 effect of the oscillating mirror 24 is to require for both horizontally and vertically reflected rays a concave focal surface, as shown at V³ and H³. The best resultant focal surface being therefore approximately 30 a concave surface, as determined principally by the combination of the curves V³ and H³; and the lenses 46, Fig. 9, should be selected with this in view.

A light source of any suitable area and 35 dimensions may be used with the apparatus and the grid widths and spacing varied to meet different optical conditions due to spreading of the light beam on account of its size. The lenses in the light beam should 40 be of different diameters and characteristics as required; and for the arrangement in Fig. 8, the lens 30 should be about three times the diameter of the lens 34; and the grid 31 should be designed with respect to the grid 45 31^a but of about three times its dimensions, provided the light source be of a diameter equal h, Fig. 7. The spacing of the grids is best determined graphically, it being understood that their function is to provide 50 a light valve in conjunction with the mirror 32, so that when said mirror is at zero deflection no light will pass through the second grid as the bars of the second grid shut off all light which passes through the apertures 55 of the first grid; and when mirror 32 is at maximum deflection all the vertical light bars which pass through the first grid should exactly register over and pass through the apertures on the second grid; intermediate 60 light values are proportional to the mirror deflection with consequent overlapping of the light beams over part of the grid bars of the second grid. The maximum mirror deflection should ordinarily be such as to cause 65 the vertical bars of light to travel horizon-

tally a distance equal to the grid spacing of the second grid. The bars of the grids should ordinarily be parallel to the axis of oscillation of the mirror 32 (or other deflecting device, such as a cathode ray oscillograph) and to the lamp filament. 70

An oblique mirror positioned in front of a rotating explorer or disk is shown in Fig. 1, of my copending application Ser. No. 715,350. The regulator of Figs. 12 and 14 may 75 be advantageously used between any source of applied energy and a part or parts whose angular or linear position is to be changed relative to the speed or direction of the said source of energy. 80

In Fig. 16, light rays from a source 35 pass through and are filtered by the grid 31^b, the rays which pass through entering the lens 120 which produces an image of the source on the plane 125 where the rays cross 85 the axis 126; these rays enter the lens 121 and are focused to produce an image of the source at or near the mirror 32 which reflects the rays to a lens 122 which focuses the rays upon the mirror wheel 27 which reflects the rays as shown and as in Figs. 8 and 9. The grid 31^c is placed near lens 122. The grids should be designed so that the rays which pass through the apertures in grid 31^b will also pass through the apertures in grid 31^c for a predetermined position or deflection of the mirror 32, generally for a maximum deflection of the mirror. A somewhat similar arrangement is shown in Fig. 28 of my application Ser. No. 715,350; and the 100 grids may be of thin metal between glass plates, as shown in Fig. 27 of the same application.

In Fig. 17, the area 123 indicates the area 105 approximately covered successively by each of the lenses 26, Figs. 1, 2, etc., at the plane of the wheel 25, said area being for best efficiency and evenness of illumination, sufficient to include the area 124 which indicates the intersection of the light beam from each 110 successive plane mirror of the mirror wheel 27 with said wheel 25; and for best results the beams from the revolving mirror should be centered successively on each of the lenses during the rotation of the lens wheel and register substantially with said lenses and follow their approximate path of travel 115 across a given arcuate area.

It is feasible to employ any other type of 120 light valve than that shown in Figs. 8 and 16; but I prefer to employ the mirror wheel 27 in combination with the lens wheel 25 and the oscillating mirror 24 all functioning and coacting to distribute the received picture point lighting values and distributing the pencils of rays reflected and refracted by them so as to register at approximately their correct positions on the receiving screen in order to faithfully reproduce at the distant 125 station an image of the scene as sent from a 130

distant station. It is obvious that the lenses may be replaced by concave focusing reflectors (not shown) or other light condensing means. The size of each lens 26 is relatively small with respect to the field of view as projected to a projection screen, and each lens in passing across the field of view requires an equal period of time when the apparatus is running at uniform speed. Each lens 26 is mounted in an aperture of the wheel 25, said wheel being of opaque material, and if these lenses be considered as relatively small with respect to the field of view, i. e., if each lens intercepts but a narrow cone of rays, then the view as projected in successive lines upon the wheel 25 may be considered as being an out-of-focus view, since each successive light beam overlaps the next light beam, said beams actually instantaneously comprising the rays to produce the true light values of adjacent picture points. The mirror 32 or 32' may be concave or convex, if desired. The use of a concave mirror is shown in my copending application Ser. No. 162,311.

I claim:

1. In apparatus for the transmission of visual images in combination, movable optical means, an electric motor for driving said means in synchronism with a second optical means, said motor being connected to said first optical means, means for producing asynchronous speed of the first optical means and simultaneously varying the power of the motor.
2. In apparatus for the transmission of visual images, in combination, movable optical means, suitable driving means connected to said optical means, and means for varying the speed of said optical means and simultaneously varying the torque of said driving means.
3. In apparatus for the transmission of visual images, in combination, movable optical means, an electric motor, the armature of said motor being connected to drive said optical means, means for varying the absolute speed of said optical means, means for increasing the power applied to the motor if the speed of the optical means is increased, means for decreasing the power applied to the motor if the speed of the optical means

is decreased, and means for restoring normal driving power to the optical means when the speed of the said optical means relative to the motor speed reaches a fixed value. 55

4. In apparatus for the transmission of visual images, in combination, movable optical means, a suitable motor for driving said means normally at a given synchronous speed, and means for momentarily producing asynchronous speed of the optical means and simultaneously maintaining substantially synchronous speed upon said motor by the application thereto of variable power. 60

5. In apparatus for the transmission of visual images, in combination, a motor, movable optical means coupled to said motor and disposed to be driven thereby, a controller for varying the relative speeds of said motor and said optical means, said controller including means connected to said motor for varying the torque between said motor and said optical means proportional to the magnitude of variation of said relative speeds. 70

6. In apparatus for the transmission of visual images, in combination, movable optical means, a motor for normally driving said means at a speed proportional to the motor speed, and means for momentarily varying the speed of said optical means relative to the motor speed and simultaneously maintaining substantially synchronous motor speed. 75

7. In apparatus for the transmission of visual images, in combination, movable optical means, a motor, a phase changer, and an electrical connection between said phase changer and said motor, said motor, phase changer and optical means being mechanically connected. 80

8. In apparatus for the transmission of visual images, in combination, movable optical means, a motor, a phase changer, and an electrical current control device, said control device, being actuated by the movement of said phase changer, and an electrical connection between said control device and said motor. 85

In testimony whereof, I, Paul L. Clark, have signed my name to this specification, 100 this 21st day of December, 1925.

PAUL L. CLARK.
